BAND PASS COUPLING SYSTEM

Rinaldo De Cola, Chicago, Ill., assignor to Belmont Radio Corporation, Chicago, Ill., a corporation of Illinois

Application April 22, 1940, Serial No. 330,881

16 Claims. (Cl. 178—44)

The present invention relates in general to band pass coupling systems, and more in particular to coupling systems of this character which are suitable for use at the intermediate frequency stages in the video channel of a television receiver. Specifically, the invention is a new and improved intermediate frequency transformer adapted to pass the comparatively wide band of frequencies used for video signals and having great attenuation for an adjacent frequency band on which audio signals are transmitted. In order to show the actual requirements, it may be stated that the general practice is to use an intermediate frequency band extending from about 8.75 megacycles to 12.75 megacycles for the video signals, which brings the audio signals for the television channel undergoing reception in at a frequency of 8.25 megacycles. The spacing of the television channels is such that the audio signals for the next adjacent television channel appear at an intermediate frequency of 14.25 megacycles. The intermediate frequency stages in the video channel of the receiver must therefore provide for uniform transmission over the range 8.75 to 12.75 megacycles, and at the same time must provide adequate attenuation for the sound signals at frequencies of 8.25 and 14.25 megacycles.

The problem of producing the desired attenuation for frequencies adjacent to the picture signal frequency band has received some attention heretofore, but the solutions proposed have not been entirely satisfactory. One type of proposed solution utilizes so-called "trap" circuits, which act as short circuits for the frequency to be attenuated, but such systems fail to produce the requisite attenuation due to the radio frequency resistance of the trap elements. Other arrangements which have been proposed are objectionable because of the extremely narrow band of frequencies over which attenuation is obtained.

The present invention affords a solution which is substantially free of the objectionable features of prior systems. It provides a coupling system for use at an intermediate frequency stage, that is, an intermediate frequency transformer, having two different circuit paths between the input and output circuits, and having the constants of the system so adjusted that at the frequency at which attenuation is desired the currents in the two-circuit paths induce equal opposing voltages in the output circuit and produce cancellation. At the same time the necessary flat response characteristic over the frequency band which is to be transmitted is maintained.

The invention thus provides an intermediate

frequency transformer which will give normal transmission of the picture frequency band, and at the same time produce relatively great attenuation of the sound channel. Moreover, attenuation is provided over a fairly good range of frequencies including the sound channel frequency, so that there is no danger that the latter will shift outside the range of attenuation during reception, as might otherwise be the case due to slight changes in the receiver oscillator frequency.

The frequency of maximum attenuation may be lower or higher than the frequency of the picture signal transmission band. In the case of a transformer designed to produce attenuation at a lower frequency, the frequency of maximum attenuation is made to coincide with the frequency of the sound carrier which is associated with the television channel undergoing reception, while if the transformer is designed to provide attenuation at a higher frequency, the attenuation frequency will be the same as the frequency of the sound carrier of the next adjacent television channel. The transformers at different stages may therefore be of two types, designed to attenuate frequencies below and above the picture signal band, respectively, whereby both adjacent sound carriers may be eliminated.

Further features of the invention will be explained in the course of the ensuing detailed description, and with reference to the accompanying drawings, in which:

Fig. 1 is a diagrammatic circuit drawing of an intermediate frequency transformer according to the invention, as used at one of the intermediate frequency stages of a television receiver;

Fig. 2 is an equivalent theoretical circuit diagram of the transformer shown in Fig. 1, which is useful in discussing the operation thereof;

Fig. 3 is a diagrammatic circuit drawing showing a modification, and Fig. 4 is the equivalent theoretical circuit diagram;

Fig. 5 is a diagrammatic circuit drawing showing a further modification, Fig. 6 being the equivalent theoretical circuit diagram;

Fig. 7 shows the physical arrangement of the transformer windings in that form of the invention which is shown in Fig. 1;

Figs. 8 and 9 show winding arrangements that may be used with the modification of Fig. 3, the arrangement of Fig. 9, with a different coil spacing, being also usable with the modification of Fig. 5;

Figs. 10 to 13, inclusive, are graphs which show selectivity curves such as may be obtained with

transformers constructed in accordance with the invention; and

Fig. 14 is a graph which shows typical phase angle curves over a range including the transmission band and attenuation frequencies.

Referring to Fig. 1, the reference character 2 indicates a vacuum tube, preferably of the pentode type, which may be an amplifier tube at an intermediate frequency stage of a television receiver. The vacuum tube 2 is provided with input terminals 3 and 4, at which connections are made from the preceding stage. A resistor 5 may be included in the cathode circuit to provide the proper bias for the control grid. The connections for the screen and suppressor grids are not shown, as they are of the usual character.

The plate circuit of tube 2 includes the battery 9, representing any suitable source of plus B potential, and also includes a tuned circuit 21 comprising the inductance 11 and the variable condenser 10. This tuned circuit may be regarded as the input circuit of the transformer.

Adjacent to the tuned circuit 21 there is shown a second tuned circuit 22, comprising the inductance 13, the variable condenser 14, and the variable resistor 15. This circuit is preferably grounded as shown.

A third tuned circuit 23 is also shown, which comprises the inductance 16 and variable condenser 18. The circuit 23 may be regarded as the output circuit of the transformer and may be connected to the grid of the pentode 20, which may be similar to the tube 2. A suitable load resistor 19 is used, shunting the condenser 18. The complete grid circuit for tube 20 includes the automatic volume control lead, as indicated.

The transformer also includes a fourth tuned circuit 24 comprising the inductance 12, inductance 17, and variable condenser 25. This circuit may be grounded as shown in the drawings.

The condensers shown in the tuned circuits may be small trimmer condensers of the mica compression type, having a range of about 5 to 15 mmf. The load resistor 19 may have a value of about 2000 ohms. The value of the resistor 15 is indicated as variable, but a fixed resistor may be used, after the correct value has been ascertained.

The inductances 11, 12, 13, 16, and 17 are the windings of the transformer and are shown in their proper physical relation in Fig. 7. The so-called universal winding is preferably used but is not absolutely essential. The coils are mounted on a small Bakelite tube 26 and are slidable relative to each other so that the coupling can be adjusted. From the positions of the coils as shown in Fig. 7, it will be seen that coil 11 is inductively coupled to coils 12 and 13, while coil 16 is inductively coupled to coils 13 and 17. This relation is also indicated in Fig. 1, where the input circuit 21 of the transformer is shown as inductively coupled to circuits 22 and 24, while the two latter circuits are shown as inductively coupled to the output circuit 23.

From the foregoing it will be appreciated that there are two circuit paths over which energy may be transmitted from the plate circuit of tube 2 to the grid circuit of tube 20. One of these paths includes the tuned circuits 21, 22, and 23, while the other path includes the tuned circuits 21, 24, and 23. Stating it another way, the input circuit 21 of the transformer is coupled to the output circuit 23 by way of two intermediate or link circuits, one of which is the tuned circuit 22 while the other is the tuned

circuit 24. In these circumstances it will be clear that voltages will be induced in the winding 16 due to the currents in circuits 22 and 24, and that the effective voltage will be equal to the vector sum of these voltages. The operation of the transformer depends on the fact that the induced voltages are essentially aiding over the picture frequency band, but at the frequency of the sound carrier, where great attenuation is desired, these induced voltages are equal and opposing, thereby reducing the effective voltage and the current in the output circuit 23 substantially to zero.

The manner in which the desired result is accomplished can be explained more conveniently with reference to the theoretical circuit Fig. 2. In this drawing the several tuned circuits are indicated by the same reference numerals as in Fig. 1, and can readily be identified. The mutual couplings between the circuits and other constants are indicated by conventional symbols.

In general, it may be stated that the selective action of the transformer depends on the proper arrangement of the polarities of the mutual coupling reactances, upon the relative phase shift between currents I_2 and I_4 which occurs over the range which includes the band of frequencies which are to be transmitted and the frequency to be attenuated, and upon changes in the relative amplitudes of the currents which take place over this frequency range.

The relation between these factors and the manner in which they affect the operation of the system can perhaps be best explained and understood with the aid of a brief mathematical analysis of the theoretical circuit, Fig. 2, which will now be proceeded with. Taking into account the four coupling reactances involved, and assuming that coupling M_4 is negative, the equation for the current I_3 in the input circuit 23 can be written in the form

$$I_3 = E \frac{|D|}{|D'|} \quad (1)$$

where D and D' are the determinants of the system. Maximum attenuation will be obtained when I_3 becomes equal to zero, or when

$$I_3 = 0 = D = M_3 M_4 Z_2 - M_1 M_2 Z_4 \quad (2)$$

where M_1, M_2, M_3 and M_4 are the mutual coupling reactances, and Z_2 and Z_4 are the impedances of circuits 22 and 24. Now Z_2 can be written with good accuracy as

$$Z_2 = R_2 (1 + j_2 \delta_2 Q_2) \quad (3)$$

and similarly Z_4 can be written as

$$Z_4 = R_4 (1 + j_4 \delta_4 Q_4) \quad (4)$$

where δ_2 is equal to

$$\frac{f - f_2}{f_2}$$

and δ_4 is equal to

$$\frac{f - f_4}{f_4}$$

the frequencies f_2 and f_4 being the resonant frequencies of Z_2 and Z_4 , respectively, and frequency f being an arbitrary attenuation frequency such as f , Fig. 14. Substituting the expressions for the impedances which are shown in Equations 3 and 4, and expressing the mutual coupling reactances in terms of the equivalent coupling coefficients, Equation 2 becomes

$$0 = (K_3 K_4 R_2 - K_1 K_2 R_4) + j_2 L_2 L_4 (K_3 K_4 \delta_2 - K_1 K_2 \delta_4) \quad (5)$$

The right hand portion of Equation 5 com-

prises two expressions which must each equal zero if the right hand portion of the equation is equal to zero. The first expression reduces to zero when

$$\frac{K_3 K_4}{K_1 K_2} = \frac{Q_2}{Q_4} \quad (\text{resistance balance}) \quad (6)$$

the symbol Q_2 being written for the expression $2\pi f L_2 / R_2$, and Q_4 being written for the expression $2\pi f L_4 / R_4$. The second expression in the right hand portion of Equation 5 reduces to zero when

$$\frac{K_3 K_4}{K_1 K_2} = \frac{\delta_4}{\delta_2} \quad (\text{reactance balance}) \quad (7)$$

A simultaneous balance is obtained, that is, Equation 5 is fully satisfied, when

$$\frac{Q_2}{Q_4} = \frac{\delta_4}{\delta_2} \quad (8)$$

From Equation 8 the equation for the frequency of infinite attenuation can readily be derived and may be written in the form of

$$f = \frac{f_1 \left(1 - \frac{Q_2}{Q_4} \right)}{1 - \frac{f_1 Q_2}{f_2 Q_4}} \quad (9)$$

In the foregoing discussion of Fig. 2, all the mutual coupling reactances were assumed to be positive, with the exception of M_4 . Various other combinations, which will reduce current I_3 to zero at a particular frequency are possible, as may be perceived from inspection of Equation 2. All these combinations satisfy the requirement that for any given combination of couplings in the two circuit paths all the couplings, except one, have the same polarity. Unless this requirement is met, cancellation in the output circuit 23 cannot result; that is, current I_3 cannot be reduced to zero.

It will be of advantage now to consider one operative arrangement of the mutual couplings more in detail, and with more emphasis on the functional working of the circuit, reference being made to the relevant equations where necessary or desirable. For this purpose the discussion of the arrangement shown in Fig. 2 may be continued.

In the assumed case, couplings M_1 , M_3 , and M_2 are positive, and coupling M_4 is negative, due to inductance L'_4 (coil 17) being reversed. With coupling M_4 negative, it will be seen, and Equation 5 indicates, that current I_3 will be reduced to zero at some particular frequency where currents I_2 and I_4 are in phase, whereby opposing voltages are induced in L_3 , provided that the current magnitudes and the concerned mutual couplings are so related that the induced voltages are equal. This last condition is satisfied if I_2/WM_2 is equal to I_4/WM_4 . The foregoing states generally the conditions as regards phase and magnitude relation of currents I_2 and I_4 which obtain at the frequency of maximum attenuation, when using the particular coupling combination under consideration.

The phase relation between currents I_2 and I_4 may be discussed more in detail with reference to Fig. 14, which shows graphically the phase angles at which the currents I_2 and I_4 lead or lag the corresponding voltages over the frequency range with which we are concerned. In this figure, f_2 is the resonance frequency of circuit 22 (Z_2) and f_4 is the resonance frequency of circuit 24 (Z_4), while I_2 and I_4 are the corresponding resonance curves. The frequency of maximum attenuation is assumed to be lower than f_2 and

f_4 and is indicated at f . Curves ϕ_2 and ϕ_4 show the manner in which the corresponding currents I_2 and I_4 lead or lag the impressed voltages at the different frequencies. At the resonance frequency the current I_2 is in phase with the voltage, as indicated by the fact that curve ϕ_2 crosses f_2 on the zero line. At frequencies higher than f_2 current I_2 has a lagging characteristic, while at lower frequencies it leads the voltage. Current

10 I_4 behaves in a generally similar manner, as indicated by curve ϕ_4 , although the phase angle changes more rapidly, due to its lower dissipation or resistance. At frequency f currents I_2 and I_4 are both leading at the same angle and are in phase with each other due to the fact that the voltages are in phase (couplings M_1 and M_3 being both positive), which gives the correct phase relation for cancellation with the negative coupling M_4 .

15 As regards the current magnitudes, it will be seen also that at frequency f , currents I_2 and I_4 are equal in magnitude, which satisfies another condition for cancellation, assuming that M_2 and M_4 are equal. It will be understood that currents I_2 and I_4 do not necessarily have to be equal

20 at frequency f , so long as the mutual couplings M_2 and M_4 are such as to produce equal induced voltages in circuit 23. It will be noticed that at frequency f both the phase angles and magnitudes of I_2 and I_4 are changing rather slowly, which accounts for the excellent attenuation over a fairly wide range including frequency f .

25 Since currents I_2 and I_4 are in phase at frequency f , the frequency of maximum attenuation, it follows that they must be out of phase, or differ in magnitude, or both, at frequencies within the picture transmission band, which includes frequencies f_2 and f_4 . This condition is also illustrated in Fig. 14.

30 As previously intimated, the attenuation frequency f of the transformer does not necessarily correspond to the sound channel frequency of 8.25 megacycles and can be shifted to a point above the picture signal frequency band, if desired, to the sound carrier frequency of 14.25 megacycles, for instance. That such shift is

35 possible will be evident from Equation 9, which shows that if frequency f_4 is lower than, frequency f_2 , then frequency f will be lower than frequency f_4 , while if frequency f_4 is higher than frequency f_2 , then frequency f is higher than frequency f_4 . This means that if frequency f is

40 to be shifted to a point above the picture transmission band, the relative positions of frequencies f_4 and f_2 as shown in Fig. 14 must be reversed; that is, frequency f_4 must be higher than frequency f_2 . Frequency f_4 can be adjusted to the proper point by varying condenser C_4 . It may also be necessary to relocate frequency f_2 , which can be done by adjusting condenser C_2 . The other constants, including resistance R_2 , will of course require readjustment. These adjustments will shortly be discussed more in detail.

45 It should be noted that in any case, and this is true of the modifications which will be described later on as well as of the one under discussion, the frequency of maximum attenuation does not correspond to the resonance frequency of any of the tuned circuits. This is an important and fundamental characteristic feature of the invention, which differentiates it from known coupling systems, in which the resonance frequency of one at least of the tuned circuits

50 always coincides with the attenuation frequency.

The calculation of the response curves of current I_3 from Equation 1 over the concerned frequency range and with the conditions required by Equations 6, 7, and 8 is possible but is exceedingly tedious. The proper adjustment of the constants of the transformer which is required in order to satisfy the equations is preferably determined experimentally, therefore.

A primary consideration, of course, is uniform transmission over the required frequency range, which is obtained by properly adjusting all four coupling factors and by adjusting the condensers C_1 , C_2 , and C_3 . These adjustments fix the limits of the frequency range at the desired points, and the load resistor R_9 associated with tuned circuit 23 produces the necessary flat top characteristic over this range. The phase characteristic from the input side of the transformer to the output side has been checked and has been found to be quite uniform over the transmission range.

The next step is to locate the attenuation frequency f , which is done by adjusting the condenser C_4 . The adjustment of this condenser fixes the location of frequency f_4 , which in turn determines frequency f , from Equation 9. In other words, the frequency f at which attenuation is to be obtained is fixed at the desired point by properly locating frequency f_4 with reference to frequency f_2 . The adjustment of condenser C_4 therefore produces the required frequency relation to satisfy Equation 7, and its effect can be visualized by reference to Fig. 14, from which it can be seen that a shift in the location of frequency f_4 will correspondingly shift the phase angle curve ϕ_4 . Thus the phase angle curve ϕ_4 is made to intersect the phase angle curve ϕ_2 at the desired attenuation frequency f .

Having made the necessary adjustments to insure that currents I_2 and I_4 will be in phase at the desired attenuation frequency, the next step is to bring the current magnitudes into the proper relation to satisfy Equation 6, which is done by adjusting the resistance R_2 . Here again the operation can be visualized from Fig. 14, from which it can be seen that if the curve I_2 were to be raised, the intersection of the current curves would occur at a frequency higher than frequency f and cancellation would not take place because the phase curve intersection and the current curve intersection would no longer be at the same point on the frequency axis. If the curve of current I_4 were to be lowered the same condition would exist, except that the current curves would intersect at too low a frequency. The value of resistance R_2 determines the height of current curve I_2 , and by adjusting this resistance the curve can be shifted up or down until it intersects curve I_4 at the desired frequency f . The phase angle curves and the current curves now intersect at the same frequency, Equation 8 is satisfied, and maximum attenuation is obtained.

The results actually obtained in practice with the transformer of Fig. 1 are illustrated by the selectivity curve Fig. 13, where attenuation is plotted against frequency. In plotting this curve the point of zero attenuation is arbitrarily fixed at the lowest point of the curve which is within the frequency range to be transmitted. Inspection of the curve shows a substantially flat response over the range extending from about 8.75 megacycles to 13 megacycles, which covers the picture signal range. It will also be evident that very great attenua-

tion is obtained at the frequency of the accompanying sound carrier, or at a frequency of 8.25 megacycles, the attenuation at this frequency being on the order of nearly 60 decibels. While the frequency range over which the great attenuation is obtained is narrow compared to the picture signal range, consideration of the frequency scale will show that at points not far from the bottom of the curve the attenuation band is many times the width of the sound channel. At 50 decibels, for instance, the attenuation band has a width of at least 250,000 cycles, while the sound signals cover a range of only about 10,000 cycles.

The selectivity curve Fig. 13 also shows a good order of attenuation for a frequency of 14.25 megacycles, which is the frequency of the sound carrier of the adjacent television channel. The excellent attenuation at 14.25 megacycles is accounted for by the direct coupling between L_1 and L_3 , and can be predicted mathematically if an additional coupling factor designating the coupling between L_1 and L_3 is introduced into Equation 1.

In the foregoing explanation it was assumed that all mutual couplings are positive except M_4 , and it has been explained in detail how cancellation is effected at a particular frequency. The transformer operates in a similar manner if the mutual coupling M_2 is negative, all other couplings being positive. Coupling M_2 can be made negative by reversing coils 16 and 17, Fig. 1, corresponding to inductances L_3 and L'_4 , Fig. 2.

A somewhat different case is presented if coupling M_3 is made negative by reversing coil 12, Fig. 1, corresponding to inductance L''_4 , Fig. 2, all other couplings including M_4 being positive. The phase relation between currents I_2 and I_4 may be essentially the same as depicted in Fig. 14, except that current I_4 is shifted in phase relative to current I_2 by 180 degrees, due to the fact that L''_4 is reversed. The phase angle curve ϕ_4 in Fig. 14 must therefore be regarded as being shifted down to a new zero axis which is 180 degrees out of phase with the zero axis shown. With this understanding, it may be stated that at frequency f currents I_2 and I_4 lead their respective voltages by the same phase angles, but are 180 degrees out of phase. As couplings M_2 and M_4 are both assumed to be positive, the voltages induced in L_3 oppose each other, and cancellation results if the proper relation exists between the current magnitudes and couplings as previously explained.

A case similar to the last described case is presented if coupling M_1 is made negative, which can be done by reversing coils 11 and 12, Fig. 1, corresponding to inductances L_1 and L''_4 , Fig. 2. It will be clear that in this case currents I_2 and I_4 will again be out of phase by 180 degrees at frequency f and that the operation will be similar to the operation just described.

All these variations come under the general rule which states that in order to effect cancellation at some desired frequency all the mutual couplings, except one, must have the same polarity, and the mathematical treatment is the same in each case.

Attention may now be directed to the modification which is shown in Fig. 3. Like Fig. 1, this figure shows two vacuum tubes 32 and 43, which are assumed to be located at adjacent intermediate frequency stages in a television receiver. The plate circuit of tube 32 is connected to the grid circuit of tube 43 by means of a modi-

fied form of the transformer shown in Fig. 1. Since the arrangement is otherwise similar to Fig. 1, it need not be described in detail.

The transformer of Fig. 3 comprises three tuned circuits 51, 52, and 53. The tuned circuit 51 includes the inductance 37 and condenser 36; tuned circuit 52 includes inductances 38 and 39 and condenser 45; while tuned circuit 53 includes inductance 40 and condenser 41. The inductances are the windings of the transformer. Two arrangements of the transformer windings or coils are possible, as illustrated in Figs. 8 and 9.

According to Fig. 8, windings 38 and 39 are combined and form a single coil which is located between the windings or coils 37 and 40. With this arrangement it will be seen that circuit 51 is inductively coupled to circuit 53 and also to circuit 52, while the latter circuit is also coupled to circuit 53. The couplings M₁, M₂, and M₃ are indicated in Fig. 8. Two circuit paths are provided between the plate circuit of tube 32 and the grid circuit of tube 43, one including the tuned circuits 51 and 53, and the other including the tuned circuits 51, 52, and 53.

In the arrangement according to Fig. 9, the windings 38 and 39 are separate coils which are located outside of coils 37 and 40, respectively. As in Fig. 8, there are three mutual couplings, M₁, M₂, and M₃. Also as in Fig. 8, two circuit paths are provided between tubes 32 and 43, one including the tuned circuits 51 and 53, and the other including all three tuned circuits. The arrangement shown in Fig. 9 has certain advantages over that shown in Fig. 8, as will be explained presently.

The operation of the transformer shown in Fig. 3 is similar in principle to the operation of the transformer shown in Fig. 1; that is, it depends upon the generation of substantially equal and opposing voltages in winding 40 at some particular frequency where attenuation is desired, which reduces the current in tuned circuit 53 to a minimum at that frequency. The operation of Fig. 3 differs in detail from that of Fig. 1, because of the fact that in Fig. 3 the two circuit paths through the transformer include an unequal number of inductive couplings, whereas in Fig. 1 the two circuit paths include an equal number of inductive couplings. The details may be brought out so far as necessary by continuing the discussion with reference to Fig. 4, which corresponds to Fig. 3 like Fig. 2 corresponds to Fig. 1.

It may first be assumed that the winding arrangement is as shown in Fig. 8. With this arrangement it will readily be seen that all the mutual couplings are positive, or at least the effect is the same as when they are, for reversing any one coil will simultaneously reverse two couplings. Reversing any two coils produces the same condition as reversing the remaining coil, and of course is equally ineffective. Assuming all couplings to be positive, therefore, the equation for the current I₃ in the output circuit 53 can be written in the form

$$I_3 = -E \frac{|D|}{|D'|} \quad (10)$$

Defining Q₂ and δ₂ as specified in the previous discussion of Fig. 2, and assuming that Q₁ and Q₃ are each equal to Q, Equation 10 can be rewritten in the form

$$I_3 = -E \frac{Q(K_2 K_3 Q_2 - 2\delta_2 Q_2 K_1 + jK_1)}{D'} \quad (11)$$

An inspection of Equation 11 indicates that 75

current I₃ can never be reduced to zero. However, the value of I₃ will be a minimum when

$$K_2 K_3 - 2\delta_2 K_1 = 0 \quad (12)$$

Equation 12 can be rewritten in the form

$$\delta_2 = \frac{K_2 K_3}{2K_1} \quad (13)$$

and from the latter equation may be derived the equation for the frequency of maximum attenuation in the form

$$f = f_2 \left(\frac{K_2 K_3}{2K_1} + 1 \right) \quad (14)$$

Equation 14 shows that the attenuation frequency can only be located above the picture transmission band, for the quantity within the parentheses is always greater than one. This fact can also be deduced from a consideration of the operation of the circuit, Fig. 4, from a functional standpoint. Bearing in mind that the three coil structure of Fig. 8 is under discussion, and that the mutual couplings are all positive, it will be appreciated that at the desired frequency of attenuation currents I₁ and I₂ must be 180 degrees out of phase with each other to produce the required opposing voltages in L₂. Since the voltage in L₂ (coil 38-39) lags the current I₁ by 90 degrees, the required phase relation between I₂ and I₁ can be obtained if current I₂ lags behind the voltage in L₂ by 90 degrees at the attenuation frequency. This theoretical condition cannot be attained in practice, due to unavoidable resistance in circuit 52, as can be seen from Equation 11. It can be approximated close enough, however, so that practical results can be secured. But the required lagging characteristic of current I₂ can only be obtained at a frequency higher than the resonance frequency f₂, which lies in the picture transmission band, and hence the attenuation frequency f must be located above the transmission band, as stated at the outset.

Fig. 10 shows a typical selectivity curve such as may be obtained with the three coil arrangement of Fig. 8. It will be noted that the maximum attenuation is not obtained at a frequency of 14.25 megacycles, but at a somewhat higher frequency. The attenuation frequency could be brought closer to the transmission band, as indicated by Equation 14, but it has been found in practice that it cannot be done without adversely affecting the required flat top characteristic of the transmission band. The curve shown indicates about the best results that can be expected with the arrangement under discussion. Although the frequency of maximum attenuation is not at the optimum point, the curve does have a much steeper slope on the high frequency side.

From the foregoing it will be seen that the practical results which can be secured with the three coil arrangement of Fig. 8 fall somewhat short of the results which might be expected from the theoretical discussion, although the selectivity of the coupling system is distinctly improved. The partial failure is due to the inflexibility of the coil arrangement as regards the adjustment of the mutual couplings. With only three coils, any change in one of the couplings changes another coupling at the same time, as can readily be seen from Fig. 8. For instance, if we change coupling M₂ by moving coil 37, we necessarily change coupling M₁ at the same time. Adjusting coupling M₃ by moving coil 40 also changes coupling M₁, and of course we cannot

adjust coupling M_1 by moving coil 37 or coil 40 without also changing coupling M_2 or coupling M_3 .

The difficulties referred to above are obviated by the four coil arrangement of Fig. 9, which is entirely flexible as regards independent adjustment of the couplings, as will be apparent from inspection of Fig. 9 and the circuit drawing, Fig. 4. To give just one example, coupling M_3 can be adjusted by moving coil 39, and this adjustment will be without effect on couplings M_1 and M_2 , for the relative positions of the coils involved in the latter couplings is not disturbed. The freedom in coupling adjustment afforded by the four coil arrangement gives greater flexibility in the choice of the attenuation frequency, which can be located close to the transmission band without affecting the flat top characteristic which is essential for the correct reception of the picture signals.

The four coil arrangement of Fig. 9 also has the advantage that the attenuation frequency may be located either above or below the picture transmission band, being somewhat comparable in this respect to the modification which is shown in Figs. 1 and 2. This freedom as to location of the attenuation frequency is accounted for by the fact that with the four coil arrangement it is possible to introduce a negative coupling. The particular coupling combination used determines the location of the attenuation frequency above or below the transmission band, as will be explained.

If all the mutual couplings are positive, the operation is similar to the operation when using the three coil arrangement insofar as the purely mathematical treatment is concerned and the case is governed by Equations 10 to 14, inclusive. The attenuation frequency is higher than the resonance frequency f_2 of circuit 52 and lies above the transmission band, as indicated by Equation 14.

For the reasons stated, however, considerably better results are secured with the four coil arrangement as compared to those obtained with the three coil arrangement. Fig. 11 is a typical selectivity curve, which shows excellent attenuation on the high frequency side of the transmission band, with a definite maximum at the frequency of 14.25 megacycles. It will be noted that the desired location of the attenuation frequency is secured without appreciable sacrifice of the flat top characteristic over the transmission band.

If a negative coupling is introduced, the attenuation frequency is moved to a location below the transmission band. To make one coupling negative, we may reverse inductance L''_2 (coil 39) or inductance L'_2 (coil 38). Reversing either coil gives one coupling factor a negative sign which requires that δ_2 be made negative also in order to satisfy Equation 12. Equation 13 then becomes

$$-\delta_2 = \frac{K_2 K_3}{2K_1} \quad (15)$$

and Equation 14 for the frequency of maximum attenuation changes to the form

$$f = f_2 \left(1 - \frac{K_2 K_3}{2K_1} \right) \quad (16)$$

Equations 15 and 16 hold independent of the location of the negative coupling. The operation of the transformer is also fundamentally the same, although the phase relation of currents I_1 and I_2 at the attenuation frequency is

different in the two cases, depending on which coil in circuit 52 is reversed in order to produce the negative coupling. This will be explained briefly.

If coupling M_3 is made negative by reversing L''_2 (coil 39), currents I_1 and I_2 must be in phase at the frequency where attenuation is desired, in order to produce opposing voltages in L_3 . Since the voltage in L''_2 lags the current I_1 by 90 degrees, the desired phase relation between currents I_1 and I_2 can be obtained if current I_2 leads the corresponding voltage by 90 degrees. This condition cannot be reached in practice, due to the resistance in circuit 52 but can be approached near enough to produce effective attenuation at the desired frequency. Since a leading current is required, the attenuation frequency must lie below the picture transmission band, as confirmed by Equation 16.

If coupling M_2 is made negative by reversing L'_2 (coil 38), couplings M_1 and M_3 being positive, currents I_1 and I_2 must be out of phase by 180 degrees at the frequency of attenuation. The reversal of L'_2 produces a phase shift of 180 degrees, which when added to the phase shift of the voltage in L''_2 with respect to I_1 , gives a phase shift of 270 degrees for current I_2 with respect to current I_1 . This phase shift will be reduced to 180 degrees at the frequency of attenuation if current I_2 leads the voltage by 90 degrees. As in the previous case, the required theoretical condition can only be approximated, but near enough for practical results.

Fig. 12 shows a typical selectivity curve for the transformer Fig. 3, using the four coil arrangement of Fig. 9 and a negative coupling. The curve shows a considerable attenuation on the low frequency side, with a frequency of maximum attenuation at 8.25 megacycles, where the transmission is down about 35 decibels. The curve of Fig. 12 is generally similar to the curve of Fig. 13. The results secured are not as good, but under certain conditions they will be entirely satisfactory.

Referring now to Fig. 5, the further modification shown therein may be described briefly. As in the previous modifications, the two vacuum tubes 62 and 83 may be located at adjacent intermediate frequency stages in a television receiver. The plate circuit of tube 62 is connected to the grid circuit of tube 83 by means of a transformer which comprises the four tuned circuits 71, 72, 73, and 74. The tuned circuit 71 includes the variable condenser 63, a fixed condenser 64, and the inductance 67. Tuned circuit 72 includes the variable condenser 65, the variable resistance 80, the inductance 66, and the fixed condenser 64. Tuned circuit 74 includes the variable condenser 75, the inductance 69, the fixed condenser 76, and the variable resistance 81. Tuned circuit 73 includes the variable condenser 77, the fixed condenser 76, and the inductance 68. The condenser 64 is shunted by a resistance 79 of about 1000 ohms to afford a direct current path for plate current. On the output side the condenser 77 is shunted by the load resistor 78.

The inductances 66, 67, 68, and 69 are the windings of the transformer and comprise four coils the physical arrangement of which may be explained with reference to Fig. 9. Coils 66 and 68 constitute a pair of coils and may occupy positions corresponding to the positions of coils 38 and 37, Fig. 9. Coils 66 and 68 accordingly are

inductively related. Coils 67 and 69 constitute a second pair of inductively related coils and may occupy the positions corresponding to the positions of coils 40 and 39 in Fig. 9. The arrangement differs from that of Fig. 9 in that the two pairs of coils are separated by a distance which is sufficient to substantially eliminate inductive coupling between pairs; that is, there should be substantially no coupling between the two inside coils. If necessary to attain this object, the core on which the coils are mounted can be made somewhat longer, or the two pairs of coils can be mounted on separate cores.

As regards the coupling between the several tuned circuits, it will be seen that the first tuned circuit 71, on which high frequency signal voltages are impressed by the plate circuit of tube 62, is inductively coupled to tuned circuit 74 by means of coils 67 and 69, while the latter tuned circuit is capacitatively coupled to tuned circuit 73 by means of condenser 76. Also, it will be seen that tuned circuit 71 is capacitatively coupled to tuned circuit 72 by means of condenser 64, while the latter tuned circuit is inductively coupled by means of coils 66 and 68 to tuned circuit 73. Thus, as in the previous modifications, two circuit paths are provided between the input and output sides of the transformer, one including the tuned circuits 71, 72, and 73, and the other including the tuned circuits 71, 74, and 73. The arrangement is similar to the arrangement of Fig. 1 in that the number of couplings is the same in the two circuit paths, being different in this respect from the arrangement of Fig. 3. The arrangement of Fig. 5 differs from both of the previous arrangements in the fact that a capacitative coupling is used in each circuit path.

The operation of the transformer may be discussed briefly with reference to Fig. 6, which is the equivalent theoretical circuit diagram, and will be understood without difficulty in view of the previous explanation. Suffice it to say that at the frequency of maximum attenuation, the currents I_2 and I_4 produce substantially equal and opposing voltages in circuit 73, which reduces the corresponding current I_3 substantially to zero. In order to effect such cancellation, it will be clear that one of the two mutual couplings M_1 and M_2 must be negative.

The mathematical analysis of the transformer is similar to that of the transformer shown in Fig. 1. Thus we may write as the equation for the current I_3 in the circuit 73

$$I_3 = \frac{|D|}{|D'|} \quad (17)$$

For cancellation of current I_3 , the determinant D must equal zero, and we may write

$$I_3 = 0 = \frac{M_1 Z_4 + M_2 Z_2}{C_2} \quad (18)$$

Equation 18 can only be satisfied if coupling M_1 or M_2 be given a negative sign. Assuming that coupling M_2 is negative and substituting equivalent expressions for Z_4 and Z_2 , Equation 18 becomes

$$0 = \frac{M_1 R_4 (1 + 2\delta_4 Q_4)}{C_2} - \frac{M_2 R_2 (1 + 2\delta_2 Q_2)}{C_4} \quad (19)$$

Collecting the resistive terms of Equation 19, we derive the equation

$$\frac{C_4 M_1 R_4}{C_2 R_2 M_2} = 1 \quad (20)$$

Collecting the reactive terms of Equation 19, we derive the equation

$$\frac{C_4 M_1 R_4}{C_2 M_2 R_2} = \frac{\delta_2 Q_2}{\delta_4 Q_4} \quad (21)$$

From Equations 20 and 21 we have

$$\frac{\delta_4}{\delta_2} = \frac{Q_2}{Q_4} \quad (22)$$

which is the equation for simultaneous balance. From Equation 22 may be derived the equation for the attenuation frequency f in the following form:

$$f = \frac{f_4 \left(1 - \frac{Q_2}{Q_4} \right)}{1 - \frac{f_4 Q_2}{f_2 Q_4}} \quad (23)$$

which is identical with Equation 9. It will be seen therefore that the attenuation frequency can be located either below or above the transmission band as desired.

In adjusting the transformer to secure maximum attenuation at the desired frequency, the variable condensers C_2 and C_4 are adjusted in order to satisfy Equation 21, that is, to produce the requisite phase relation between currents I_2 and I_4 at the desired attenuation frequency, after which the resistances R_2 and R_4 are adjusted to satisfy Equation 20, which insures the requisite relationship as regards the magnitudes of currents I_2 and I_4 .

No selectivity curve is shown for the transformer of Fig. 5, but it may be stated that the results obtained are comparable with those obtained with the transformer of Fig. 1, insofar as attenuation at some selected frequency is concerned. Assuming that the transformer is adjusted for attenuation at 8.25 megacycles on the lower side of the transmission band, reference may be made to Fig. 13 to ascertain the amount of attenuation at this frequency. That is, the low side of the selectivity curve for Fig. 5 is substantially the same as shown in Fig. 13. There is, however, no additional attenuation on the high frequency side as shown in Fig. 13, but the curve on this side is about the same as is shown in Fig. 12. Of course, the frequency of attenuation f can be moved to the upper side of the transmission band, if desired, in which case there would be no additional attenuation on the low frequency side, the lower side of the curve being similar to the lower side of the curve in Fig. 10.

The invention having been described, that which is believed to be new and for which the protection of Letters Patent is desired will be pointed out in the appended claims.

I claim:

1. In a band pass coupling system for transmitting frequencies within a given frequency band, an input circuit including a coil, an output circuit including a second coil inductively coupled to said first coil, a third circuit including a third coil inductively coupled to said first and second coils, and means including said couplings for tuning said circuits so that the frequencies within said band are transmitted with substantially uniform response while at a frequency close above said band the current in the third circuit has a lagging phase angle approaching 90 degrees, whereby the currents in the input circuit and said third circuit differ in phase by an angle approaching 180 degrees and the voltages induced in the output circuit approximately cancel each other.

2. In a band pass coupling system for transmitting frequencies within a given frequency band, an input circuit including a coil, an output circuit including a second coil inductively coupled to said first coil, a third circuit including two coils which are inductively coupled to said first and second coils, respectively, all said couplings having the same polarity, and means including said couplings for tuning said circuits so that frequencies within said band are transmitted with substantially uniform response while at a frequency close above said band the current in the third circuit has a lagging phase angle approaching 90 degrees, whereby the currents in the input circuit and said third circuit differ in phase by an angle approaching 180 degrees and the voltages induced in the output circuit approximately cancel each other.

3. In a band pass coupling system for transmitting frequencies within a given frequency band, an input circuit including a coil, an output circuit including a second coil inductively coupled to said first coil, a third circuit including a third coil inductively coupled to said first coil and a fourth coil inductively coupled to said second coil, said last mentioned coupling being negative and all other couplings being positive, and means including said couplings adjusted to cause the current in said third circuit to lead its voltage by a phase angle approaching 90 degrees at a frequency close adjacent the lower side of said frequency band, whereby the currents in said input and third circuits are approximately in phase at such frequency and the voltages induced in said output circuit approximately cancel each other.

4. In a band pass coupling system for transmitting frequencies within a given frequency band, an input circuit including a coil, an output circuit including a second coil inductively coupled with said first coil, a third circuit including a third coil inductively coupled with said second coil and a fourth coil inductively coupled with said first coil, said last mentioned coupling being negative and all other couplings being positive, said last mentioned coupling and the negative polarity thereof tending to produce a 270 degree phase shift between the currents in said third circuit and said input circuit, and means for reducing said phase shift to approximately 180 degrees at a frequency close adjacent the lower side of said frequency band, whereby the voltages induced in said output circuit approximately cancel each other.

5. In a band pass coupling system for transmitting frequencies within a given frequency band, an input circuit, an output circuit, an intermediate circuit capacitatively coupled to said input circuit and inductively coupled to said output circuit, a second intermediate circuit inductively coupled to said input circuit and capacitatively coupled to said output circuit, and tuning means for said circuits including said couplings so adjusted that substantially uniform transmission is obtained over said frequency band whereas at a particular frequency outside said band voltages are produced in said output circuit which substantially cancel each other.

6. In a transformer for a band pass coupling system, four coils arranged in pairs and so positioned relative to each other that the coils of each pair are inductively related whereas the coupling between coils of different pairs is substantially zero, an input circuit including a coil of one pair, an output circuit including a coil of

the other pair, two link circuits including, respectively, the other coils of said pairs, and condensers coupling said link circuits, respectively, to the output and input circuits.

5 7. In a transformer for a band pass coupling system, four coils located in spaced parallel planes on a common axis, said coils being movable along said axis to vary the coupling between adjacent coils, input and output circuits including the second and third coils, respectively, a circuit including the first and fourth coils, for transferring energy from the input to the output circuit in addition to that transferred by the coupling between said second and third coils and means for tuning each of said circuits.

10 8. In a transformer for a band pass coupling system, five coils located in spaced parallel planes on a common axis, said coils being movable along said axis to vary the coupling between adjacent coils, input and output circuits including the second and fourth coils, respectively, a circuit including the third coil inductively coupled thereby to said input and output circuits, a circuit including the first and fifth coils inductively coupled to said input and output circuits by said first and fifth coils, respectively, and means for tuning each of said circuits.

15 9. In a band pass coupling system for transmitting frequencies within a given frequency band, a tuned output circuit, second and third circuits inductively coupled to said output circuit, said couplings having unlike polarities, means for dividing an incoming signal between said second and third circuits in such manner that the voltage components in said second and third circuits are in phase, and tuning means including said couplings for tuning said second and third circuits to different frequencies within said frequency band, said tuning means and other constants being so adjusted that in the vicinity of a predetermined frequency adjacent said frequency band the phase angles by which the currents in the second and third circuits are shifted from their respective voltages are changing slowly and are equal at said predetermined frequency, while at frequencies within said band said currents differ in phase, the phase difference being so related to the magnitude of the currents that substantially uniform transmission is obtained over said band.

20 10. In a band pass coupling system for transmitting frequencies within a given frequency band, a tuned output circuit, second and third circuits inductively coupled to said output circuit, said couplings being of like polarities, means for dividing an incoming signal between said second and third circuits in such manner that the voltage components in the two circuits are 180 degrees out of phase, and tuning means including said couplings so adjusted that in the vicinity of a predetermined frequency adjacent said frequency band the phase angles by which the currents in the second and third circuits are shifted from their respective voltages are changing slowly and are equal at said predetermined frequency.

25 11. In a band pass filter, an output circuit, second and third circuits coupled to said output circuit, means for dividing incoming signal currents between said second and third circuits, and means for tuning said second and third circuits to different frequencies within a desired frequency band, the said tuning means and other constants of said filter being so adjusted that near the center of said band the transmission of energy to the output circuit is predominantly

due to the difference in phase relation of the currents in the second and third circuits while near the extremities of the band the transmission is mainly due to the difference in the magnitude of said currents, the adjustment of said tuning means and other constants being such also that at a frequency close outside said band the said currents have the proper phase relation and magnitude to induce equal and opposing voltages in said output circuit.

12. In a band pass coupling system for transmitting frequencies within a given frequency band, an output circuit, second and third circuits to which said output circuit is connected by inductive couplings, one of said couplings being negative, means for dividing incoming signals between said second and third circuits, means for tuning said second and third circuits to different frequencies within said band, means including said tuning means for causing the currents in said second and third circuits to differ most widely in phase at the frequency in said band at which they are equal in magnitude, said last means being also effective to cause said currents to coincide in phase at a selected frequency outside said band, and means for adjusting the relative magnitudes of said currents so that at said selected frequency the opposing voltages induced in said output circuit are equal.

13. In a band pass coupling system for transmitting frequencies within a given frequency band, an input circuit, second and third circuits connected to said input circuit by inductive couplings, said couplings being of like polarity, an output circuit connected to said second and third circuits by inductive couplings, said last mentioned couplings being of unlike polarity, means for tuning said input and output circuits and the said second circuit to fix the limits of said frequency band, means for tuning said third circuit to a frequency within said band but different than the frequency to which the second circuit is tuned, means for adjusting the impedance resistance ratios of said circuits to different values correlated with the tuning and coupling factors, whereby the currents in the second and third circuits are caused to differ in phase throughout said frequency band and to coincide in phase at a selected frequency adjacent to but outside said frequency band, and means for adjusting the relative magnitudes of said currents so that at said selected frequency equal voltages are induced in said output circuit.

14. A band pass coupling system as claimed in claim 13, wherein the couplings of unlike polarity are associated with the input circuit rather than the output circuit, whereby the phase difference which exists between the currents in the

second and third circuits at any frequency is augmented by 180 degrees.

15. In a band pass filter system for transmitting frequencies within a given frequency band, first and third circuits constituting input and output circuits, respectively, second and fourth circuits disposed in parallel relation between said input and output circuits, inductive couplings connecting the input circuit with said second and fourth circuits, inductive couplings connecting the second and fourth circuits with said output circuit, one of said couplings being negative, and tuning means in said circuits so adjusted that substantially uniform transmission is secured over said frequency band while at a frequency of maximum attenuation adjacent said band but outside thereof the currents in the second and fourth circuits induce substantially equal and opposing voltages in said output circuit, the frequency of maximum attenuation being determined by the equation

$$f = \frac{f_1 \left(1 - \frac{Q_2}{Q_4} \right)}{1 - \frac{f_1 Q_2}{f_3 Q_4}}$$

in which f represents the frequency of maximum attenuation, f_1 and f_3 the resonant frequencies of the second and fourth circuits, respectively, and Q_2 and Q_4 the impedance resistance ratios of the second and fourth circuits, respectively.

16. A transformer for transmitting signals over a given frequency band and having a non-symmetrical transmission curve showing a frequency of maximum attenuation only on one side of said band but either above or below the same, said transformer comprising an output circuit, second and third circuits coupled to said output circuit, means for dividing incoming signals between said second and third circuits, tuning means including the mutual couplings, capacity, inductance, and resistance of said circuits, the second and third circuits being tuned to different frequencies in said band and the second or the third circuit having the higher frequency depending on whether the frequency of maximum attenuation is to be located below or above said band, and the said tuning factors being so related that substantially uniform transmission of signals to the output circuit is obtained at frequencies within said band whereas at the frequency of maximum attenuation but not at frequencies immediately above or below the same the currents in said second and third circuits are so related in phase and magnitude that substantially equal and opposing voltages are induced in said output circuit.

RINALDO DE COLA.
